(57) **CLAIM**

The ornamental design for a scope warmer apparatus, as shown and described.

DESCRIPTION

FIG. 1 is a perspective view of a scope warmer apparatus;

FIG. 2 is a front end view thereof;

FIG. 3 is a back end view thereof;

FIG. 4 is a left side view thereof;

FIG. 5 is a right side view thereof;

FIG. 6 is a top view thereof; and,

FIG. 7 is a bottom view thereof.

The broken lines in FIG. 2 illustrate a portion of the scope warmer apparatus that forms no part of the claimed design.
